FIG. 1

FIG. 2

FIG. 3

FIG. 5

FIG. 4

FIG. 6

FIGURE 1 is a front, right end and bottom perspective view of a weatherproof electrical outlet box cover showing our new design;

FIGURE 2 is a top plan view;

FIGURE 3 is a front elevational view;

FIGURE 4 is a bottom plan view;

FIGURE 5 is a right side elevational view, the opposite side being substantially a mirror image thereof; and

FIGURE 6 is a rear elevational view.

The stippled portion of FIGURE 6 indicates a contrasting appearance resulting from use of a gasket material.

We claim:

The ornamental design for a weatherproof electrical outlet box cover, as shown and described.
